George C. Mayes

INVENTOR

A. L. Beck

BY *Wm. H. Ho.*

ATTORNEYS

UNITED STATES PATENT OFFICE.

ANDREW LEE BECK, OF ORLANDO, FLORIDA.

CALCULATOR.

Application filed September 7, 1922. Serial No. 586,750.

To all whom it may concern:

Be it known that I, ANDREW LEE BECK, a citizen of the United States, and a resident of Orlando, in the county of Orange and

5 State of Florida, have invented certain new and useful Improvements in Calculators, of which the following is a specification.

This invention relates in general to calculators, and more particularly to an 10 improvement in lumber calculators of the type forming the subject-matter of my copending application, filed Dec. 16, 1921, Serial No. 522,815.

The object of the invention is to provide 15 an extremely simple and durable lumber calculator which may be readily operated and manipulated to enable the user to ascertain the number of board feet contained in any given number of pieces of lumber 20 of any given dimensions without the necessity of carrying out any mathematical calculations or processes.

Other objects and advantages of the 25 invention reside in certain novel features of the construction, combination and arrangement of parts which will be hereinafter more fully described and particularly pointed out in the appended claims, reference being had to the accompanying 30 drawings forming part of this specification, and in which:

Figure 1 is a perspective view, illustrating the preferred embodiment of the invention;

Figure 2 is a view thereof in longitudinal 35 vertical section; and

Figure 3 is a fragmentary view in elevation, illustrating a portion of the chart.

Referring to the drawings wherein for 40 the sake of illustration is shown the preferred embodiment of the invention the numeral 10 designates side plates which with the table 11 make up the frame of the calculator. The side plates 10 are provided with bearing slots 12 open at their upper

45 ends and with inclined faces or seats 13. A chart bearing cylinder or roller 14 is provided and is formed with trunnions 15 which are rotatably received in the bearing slots 12. An indexing bar 16 is supported

50 upon the inclined faces or seats 13 and is

fastened thereto. The arrangement is such that when the bar 16 is assembled with the side plates it is cooperatively disposed with respect to the chart on the cylinder 14. Moreover it serves to maintain the cylinder 55 in position that is it prevents displacement of the trunnion 15 of the cylinder from the groove 12. Preferably the fastening means 17 which serves to secure or fasten the index bar to the inclined faces or sides 60 13 comprise screws or other removable and releasable devices, thus providing for disassembly if desired.

The chart which is wrapped around the cylinder 14 corresponds substantially with 65 the chart or table employed in the device forming the subject-matter of my copending application and includes as before groups of figures, designated at 20, which represent the length in feet of the boards 70 and a plurality of sets of figures 21 arranged adjacent each group 20 and representing in inches the width and thickness in which the lumber of adjacent groups comes. The body of the chart is provided with horizontal 75 and vertical lines, as before, but in this case the lines extend circumferentially and transversely when the chart is wrapped on the cylinder and these lines provide the spaces in which the computed figures 22 are 80 disposed. The index bar carries a series of numbers 24 which represent the number of pieces of lumber computed. It is obvious that when the cylinder is turned to bring the number of the group 20 immediately 85 above the index bar, the number of board feet in any given number of pieces of lumber may be immediately ascertained by observing the particular computed number which is disposed immediately above and 90 adjacent to the number of the series 23 of the index bar which corresponds to the number of pieces of lumber to be computed.

I claim:

1. A calculator comprising a frame, a 95 chart bearing cylinder rotatably mounted on the frame, a combined indexing and retaining bar secured to the frame and cooperable with the cylinder.

2. A calculator comprising side plates 100

having vertical bearing slots open at their upper ends and also provided with inclined faces, a chart bearing cylinder having trunnions rotatably received in said bearing slots, and an index bar seated against the inclined faces of the side plates and secured thereto, the index bar being thus cooperatively disposed with respect to the chart bearing cylinder and engageable with the cylinder to prevent displacement of the trunnions of the cylinder from the bearing slots.

ANDREW LEE BECK.
